CLAIM

What is claimed is the ornamental design for a smart GPS charm, as shown and described.

DESCRIPTION

FIG. 1 is a top perspective view showing of the smart GPS charm of Applicant's new design.

FIG. 2 is a bottom perspective view of smart GPS charm of FIG. 1.

FIG. 3 is a front plan view of the smart GPS charm of FIG. 1, the back plan view, the left plan view, and the right plan view being an identical mirror image thereto.

FIG. 4 is a top plan view of the smart GPS charm of FIG. 1; and,

FIG. 5 is a bottom plan view of the smart GPS charm of FIG. 1.

The word and teardrop design with "FINDYA" forming part of the claimed design is a trademark of Laura G. Cheston.
